UNITED STATES PATENT OFFICE.

MAX WILLINGER, OF NEW YORK, N. Y.

SCRAP-BOOK, &c.

No. 887,448.

Specification of Letters Patent.

Patented May 12, 1908.

Application filed December 20, 1907. Serial No. 407,407.

To all whom it may concern:

Be it known that I, MAX WILLINGER, formerly a subject of the Czar of Russia, but having declared my intention of becoming a 5 citizen of the United States, and residing in the borough of Manhattan, city, county, and State of New York, have invented certain new and useful Improvements in Scrap-Books, &c., of which the following is a specification.

10 My improvements relate to the class of books used for filing and exhibiting various articles, such as post cards, pictures, letters, prescriptions, samples and the like, where 15 the thickness of the articles to be so filed is to be compensated for by fillers interposed between certain pages.

15 My main object is to afford a simple cheap structure in which the stitching together of 20 the signatures is rendered unnecessary, while greater strength is attained, and the book at the same time is adapted to be opened flat to the fullest extent without injury to the parts.

The distinguishing feature of the invention 25 consists essentially in arranging and utilizing the filler folds in such manner that they answer not only as fillers but also as a means of uniting the several signatures as herein-after described and claimed specifically.

30 In the accompanying drawings I have shown my invention as applied, by way of illustration, to an album for post cards, although I do not restrict myself thereto since my method of forming and securing together 35 the filler folds of the signatures is adapted to books of various other kinds in which papers or other articles are to be inserted.

Figure 1, is a view of a portion of one of the 40 end signatures; Fig. 2, is an edge view of a portion thereof on a larger scale, showing the filler fold; Fig. 3, is a view of a portion of the center of one of the intermediate signatures marked for folding; Figs. 4, 5 and 6, are partial edge views upon an enlarged scale illustrating the method of folding; Fig. 7, a similar view illustrating the joining of two intermediate signatures; Fig. 8, is a view of a portion of the album open flat; Fig. 9, is an enlarged and exaggerated edge view of the central portions of the signatures and back to illustrate clearly the structure and its flexibility; Fig. 10, is a detail upon the same enlarged scale of the central portion of a single signature.

55 The main portion of the book is composed of any suitable number of folded sheets or

signatures S. These signatures each consist of a sheet of paper or other suitable material of such size and shape as to form two leaves 2, 2, when folded centrally, on the line 3. 60

In preparing the sheet to form the signature lines 4 and 5 parallel to the center line 3 are formed, marked or inscribed in any suitable manner, the object being to indicate the line of, and facilitate, the folding of the central portion of the sheet to form the fillers 6, 6.

The inner opposed surfaces of the filler folds 6, 6, are pasted, glued or otherwise caused to adhere positively together. It will 70 be noted that the width of fold between 3 and 4 is greater than that between 4 and 5 so that the central bight or angle is not cramped but has sufficient margin to insure an easy play by and between the leaves when the filler 75 folds or adjoining signatures are secured together.

In Fig. 4, the method of folding is indicated. In Fig. 5 the inner opposed surfaces of the folds between 3 and 4 and 4 and 5 are 80 shown as glued or otherwise secured together, and Fig. 6 shows them thus united but with the leaves 2, 2, of the signatures S, slightly apart. Fig. 7, shows the outer surface of one filler fold on one signature S 85 pasted, glued or otherwise caused to adhere positively to the opposed surface of one of the filler folds of the next adjoining signature S, and in this way the body of the book is built up and assembled,—the distinguishing feature 90 in this connection being the forming of a filler fold 6 on each side of superposed leaves 2, 2, forming the signature, so that said filler folds not only act as fillers, but also are available as means whereby adjoining signatures 95 may be glued or otherwise permanently caused to adhere together through the medium of said filler folds in such manner as to permit of the free articulation of all leaves. This arrangement of the filler folds 6, one on 100 each side of the leaves 2, 2, forming a signature is illustrated clearly upon an enlarged scale in Fig. 10, and in Fig. 9, upon the same enlarged scale, the attachment and relation to each of the several intermediate 105 signatures through the medium of their respective filler folds is shown. By this construction and arrangement of parts I secure a flexibility of connection that admits of the opening of the leaves freely and flatly, or essentially so, as indicated in Figs. 8 and 9, by reference to which latter it will be under- 110

stood that the articulation of the leaves is practically unrestricted, and that the book may be opened at any page and spread out horizontally if desired, since the central portions 33, of the several signatures S form collectively a flexible ligature which is free to adapt itself to all the requirements of use. In other words, considered as a backing, and with relation to the body of the book, this 10 flexible ligature or connection by which the several signatures are coupled together can assume either a convex or a concave position with equal facility and without uneven strain or tension on the parts, even when attached 15 to a stiff backing B, and side boards or covers b, b, as shown in said Figs. 8 and 9.

When thus attached to a back B, and side covers b, b, I prefer to form the first and last signatures of the book with but a single filler 20 fold 66, for purpose of attachment to the filler fold of the next adjoining intermediate signature,—the outer or end leaf in each case being pasted or otherwise secured to the cover board b, on that side of the book, although this construction and arrangement of 25 end signatures is not essential or indispensable, and I do not confine myself thereto.

It is to be noted particularly that by my construction what is practically a single filler 30 of four thicknesses of material is interposed between adjoining intermediate signatures,—said filler consisting of the united folds of two adjoining signatures, and affording ample compensation or accommodation for 35 the thickness of the cards or other articles inserted in or imposed upon the pages, and

at the same time constituting the means of attachment between the several signatures.

By dispensing with the stitching I obviate the various practical objections thereto and 40 at the same time attain a more substantial structure.

What I claim as my invention and desire to secure by Letters Patent is,

1. In a book of the character designated, a 45 series of signatures each consisting of a folded sheet the central portion of which is formed with two filler folds, one on each side of the signature, the opposed surfaces of the filler folds on adjoining signatures being glued or 50 otherwise made to adhere to each other, for the purpose described.

2. In a book of the character designated, the combination with a book cover, of a series of intermediate signatures each consisting of a folded sheet the central portion of which is formed with two filler folds, one on each side of the signature, the opposite surfaces of the filler folds of adjoining signatures being made to adhere together, and end 55 signatures consisting each of a folded sheet having a single filler fold made to adhere to the opposed filler fold of the adjacent intermediate signature, each of said end signatures being also attached by one leaf to the 60 adjoining cover board, for the purpose described.

MAX WILLINGER.
